UNITED STATES PATENT OFFICE.

GEORGE CROMPTON AND HORACE WYMAN, OF WORCESTER, MASSACHUSETTS, ASSIGNORS TO SAID GEORGE CROMPTON.

MECHANICAL MOVEMENT.

SPECIFICATION forming part of Letters Patent No. 339,048, dated March 30, 1886.

Application filed January 22, 1886. Serial No. 189,435. (No model.)

To all whom it may concern:

Be it known that we, GEORGE CROMPTON and HORACE WYMAN, both of Worcester, county of Worcester, and State of Massachusetts, have invented an Improvement in Mechanical Movements, of which the following description, in connection with the accompanying drawings, is a specification, like letters on the drawings representing like parts.

10 This invention has for its object to provide a mechanical movement wherein the end of a main lever of the third order may be placed in any one of six different positions, and be there held at rest and be moved from any one 15 to any other of the said six different positions in the same time, as will be described.

The mechanical movement herein to be described contains a main lever of the third order pivoted upon an auxiliary lever of the third 20 order. The main lever of the third order has attached to it between its ends a cord or chain extended over a pulley or block, and the opposite end of the said cord or chain is attached to a connecting-rod. The auxiliary lever of the 25 third order at one end has attached to it a cord or chain, which is extended over a second pulley or block of smaller diameter, and the said cord or chain is attached to a connecting-rod, and the other end of the said auxiliary lever 30 has its fulcrum on a pin at the end of a third connecting-rod, all three of the connecting- rods referred to engaging cranks on three semi-rotating wheels.

The particular features in which this invention 35 consists will be hereinafter described, and then pointed out in the claim at the end of this specification.

Figure 1 is a side elevation of a mechanical movement embodying this invention; Fig. 2, 40 plan or top view of the same, the sheave at the left of Fig. 1 and the cord and weight being broken off; Fig. 2^a, a detail showing the stud or fulcrum for the two pulleys; and Figs. 3 to 8, inclusive, are diagrams showing the main lever 45 and its actuating parts in different positions.

A represents a part of the frame-work of a machine wherein the mechanical movement herein to be described is to be employed. This frame, as herein shown, has a stud, A', on

which are placed three wheels, g h i, each provided with a crank, the latter having joined to them, respectively, the connecting-rods g' h' i'. The wheels g, h, and i will in practice be toothed at their peripheries, and supported as described in United States Patent No. 55 281,842, and will be turned at the proper times by long gears, substantially such as shown in the said Patent No. 281,842, to which reference may be had. The frame A has also attached to it, as best shown in Figs. 2 and 2^a, a fulcrum 60 or stud, a, upon the body of which is mounted the small pulley b, the said stud having an offset portion provided with a pin, c, on which is mounted a large pulley, d, the said pulleys being thus mounted eccentrically with relation 65 to each other. The main lever n—a lever of the third order—has its fulcrum at 10 on the auxiliary lever o, having its fulcrum at 12 on the connecting-rod i'. The free end of the main lever, which is to be moved into any one 70 of six different positions, has attached to it a cord or chain, p, extended over a sheave, p', on a stud, p², the said cord or chain having joined to it a weight or other article to be moved, the weight of which is sufficient to 75 counterbalance the weight of the levers n and o. The lever n has attached to it one end of a cord or chain, d², which, extended about the pulley d, is joined to the connecting-rod g', and the free end of the auxiliary lever o has 80 attached to it one end of a cord or chain, b², which, extended over the pulley b, is joined to the connecting-rod h'.

The cord or chain p may be attached to a guided vertically-movable rod, instead of to 85 the weight p³.

In the diagram, Fig. 3, wherein the free end of the lever n is opposite the station 1, the wheels g and i are in such position that their crank-pins stand at the right of the stud A', 90 the crank-pin of the wheel h standing at the left of said stud. To bring the end of the lever n to station 2, the wheel i will be turned from the position Fig. 3, to place its crank-pin at the left of the stud A', as in Fig. 2^a. 95 To bring the lever n to station 3, it will be necessary, with the parts in the position Figs. 2 to 4, to turn the wheel h and place its crank-

pin at the right of the stud A'. To bring the end of the lever *n* to station 4 from station No. 3, the wheel *i* will be turned to place its crank-pin on the right of the stud A', and the 5 wheels *g* and *h* will be turned to place their crank-pins at the left of the said stud, as in Fig. 6. To bring the end of lever *n* to station 10 5 from station 4, it is only necessary to turn wheel *h* from the position diagram Fig. 6 to the right of the stud A', as in Fig. 7, and to bring the end of the lever *n* to station 6 from station 5 the wheel *i* will be turned to place its 15 crank-pin to the left of the stud A', as in Fig. 8. To move the lever *n* from station 2, as represented in Fig. 4, to station No. 5, as in Fig. 7, the wheels *g* *h* *i* will each be turned a half-rotation.

By contrasting the diagrams, Figs. 3 and 8, indicating, respectively, positions 5 and 6, it 20 will be noticed that the cranks of the wheels in Fig. 8 are placed just the reverse of those shown in Fig. 3, and the same is true of Figs. 5 and 6.

Among other things for which the mechani-

cal movement herein described is especially 25 applicable is the movement of shuttle-boxes in looms, or for the movement of a lever or rod which for any reason is at times to have a variable throw or stroke.

We claim—

Three wheels having crank-pins, three connecting-rods joined to the said crank-pins, two pulleys, and a main and an auxiliary lever of the third order, one having its fulcrum on the other, combined with two cords or chains, each 30 extending from one connecting-rod about one of the said pulleys, and being joined at its opposite end to one of the said levers below its fulcrum, to operate substantially as described.

In testimony whereof we have signed our 40 names to this specification in the presence of two subscribing witnesses.

GEO. CROMPTON.
HORACE WYMAN.
